CONTROL SYSTEM

Filed Dec. 18, 1925

UNITED STATES PATENT OFFICE.

DAVID C. PRINCE, OF SCHENECTADY, NEW YORK, ASSIGNOR TO GENERAL ELECTRIC COMPANY, A CORPORATION OF NEW YORK.

CONTROL SYSTEM.

Application filed December 18, 1925. Serial No. 76,332.

My invention relates to control systems, and has for its principal object the provision of an improved system for controlling the transmission of current through an electron discharge device such as a mercury arc rectifier connected between load and supply circuits.

It is customary to interconnect an alternating current supply circuit and a load circuit through means comprising a transformer and a mercury rectifier and to connect equalizing transformers between the rectifier anode leads having the same polarity for the purpose of ensuring the proper distribution of current between these anodes. When a mercury rectifier is utilized to transmit current between an alternating current supply circuit and a load circuit connected to an electrical locomotive or the like, it is desirable both to limit the number of main transformer taps used to step up and step down the voltage of the load circuit and to effect these steps in the load circuit voltage without interrupting the load circuit connections. In accordance with my invention, these results are produced by correlating changes in the main and equalizing transformer connections in a manner to maintain the load circuit connections while the load circuit voltage is changed by a series of steps which greatly exceed the number of main transformer taps through which these steps in voltage are produced.

My invention will be better understood from the following description when considered in connection with the accompanying drawing and its scope will be pointed out in the appended claims.

The drawing shows a control system wherein my invention has been embodied.

This system comprises a machine 1 to which current is supplied from an alternating current circuit 2 through a transformer winding 3 grounded at a point intermediate its ends, a control device 4, and a mercury rectifier 5 which comprises anodes 6, 7, 8 and 9 and a cathode 10.

The control device 4 comprises stationary contact members 11 to 32 and movable contact members 33 to 38. The movable contacts are mounted on a rotatable drum or the like which may be operated to move the contact 33 successively into engagement with the contacts 14, 13, 12 and 11, the contact 34 successively into engagement with the contacts

18, 17, 16 and 15, the contact 35 successively into engagement with the contacts 22, 21, 20 and 19, the contact 36 successively into engagement with the contacts 26, 25, 24 and 23, the contact 37 successively into engagement with the contacts 29, 28 and 27, and the contact 38 successively into engagement with the contacts 32, 31 and 30.

The main transformer secondary winding 3 is grounded at the center and its upper and lower portions are provided with taps 39 to 42 and 43 to 46 respectively. It will be observed that the taps 39, 40, 41, 42, 43, 44, 45, and 46 are respectively connected to pairs of stationary segments 14 and 18, 13 and 17, 12 and 16, 11 and 15, 22 and 26, 21 and 25, 20 and 24, and 19 and 23. The contacts 33 and 34 are connected to anodes 6 and 7 through the windings 47 and 48 of an equalizing transformer 49. The movable contacts 35 and 36 are likewise connected to anodes 8 and 9 through the windings 50 and 51 of an equalizing transformer 52. The movable contacts 37 and 38 are connected to the lower terminals of the equalizing transformer windings 47 and 50 respectively and the upper terminals of these windings are respectively connected to groups of stationary contacts 27, 28 and 29 and 30, 31 and 32. The controller 4 is operable to different positions which are indicated by the letters A, B, C, D, E, F, G and H. It will be readily understood that the potentials of the transformer taps 39, 40, 41 and 42 are equal in value and opposed in phase to the potentials of the taps 43, 44, 45 and 46 respectively.

With the controller in the position A, the circuit between the main transformer and the rectifier is interrupted and no current is supplied to the load circuit to which the motor 1 is connected. Movement of the controller to the position B causes a voltage corresponding to the transformer taps 39 and 43 to be applied to the load circuit. When the controller is moved to the position C, the anodes 7 and 9 are connected to the lowest voltage taps of the main transformer winding 3 while the anodes 6 and 8 are connected to the next to the lowest voltage taps of this winding. Under these conditions, the anodes 6 and 8, which are operating at a higher voltage than the anodes 7 and 9, tend to carry all the current transmitted through the rectifier and would transmit all this current but for the fact that the equalizing

transformers function to maintain a proper distribution of current between the anodes. This current is transmitted at a voltage which is the average of the lowest and next to the lowest tap voltages of the main transformer winding 3.

Operation of the controller 4 to the position D produces three different resulting steps. The first step results in short circuiting of the equalizing transformer windings 47 and 50 due to engagement of contacts 37 and 38 with contacts 29 and 32 respectively, thus causing the arcs of the rectifier to be transferred to the anodes 6 and 8 and raising the load circuit voltage to a value corresponding to the second voltage tap of the main transformer. The second step results in the connection of the anodes 7 and 9 to the same respective transformer taps as the anodes 6 and 8 due to engagement of contacts 34 and 36 with the segments 17 and 25 respectively. The third step results in removal of the short circuits from the equalizing transformer windings 47 and 50 due to disengagement of the contacts 37 and 38 from the segments 29 and 32, thus causing current to be equalized between the anodes at a voltage which still corresponds to the second tap of the main transformer winding 3.

Transfer from the voltage corresponding to the low voltage transformer taps to that corresponding to the next highest voltage transformer taps is thus made by raising the voltage of anodes 6 and 8, equalizing the currents between the anodes 6 and 7 and between the anodes 8 and 9 to produce a voltage between that corresponding to the first and second voltage taps of the main transformer, short circuiting windings 47 and 50 of the equalizing transformers to cause the voltage at which current is transmitted through the rectifier to be raised to a value corresponding to the second transformer tap, changing the connections of the anodes 7 and 9 to the second transformer tap while current is carried by the anodes 6 and 8 at a voltage corresponding to the second taps, and removing the short circuits from the equalizing transformer windings to cause current to be equally divided between the anodes 6, 7, 8 and 9 at a voltage corresponding to the second taps. Additional steps in raising the load circuit voltage are performed in the manner just described and will be readily understood without further explanation.

It will be apparent that for each succeeding transformer tap voltage at least two different voltages will be applied to the load circuit. This method of operation therefore has the great advantage that the number of voltage steps is increased without correspondingly increasing the number of main transformer taps and without inter-

rupting the connections of the load circuit.

The embodiment of the invention illustrated and described herein has been selected for the purpose of clearly setting forth the principles involved. It will be apparent, however, that the invention is susceptible of being modified to meet the different conditions encountered in its use and I therefore aim to cover by the appended claims all modifications within the true spirit and scope of my invention.

What I claim as new and desire to secure by Letters Patent of the United States is:

1. The method of controlling a circuit supplied with current through a mercury vapor arc device wherein anodes of like polarity are interconnected through an equalizing transformer, which comprises applying different voltages to said anodes, equalizing the currents of said anodes for applying to said circuit a voltage intermediate said voltages, and short circuiting a winding of said equalizing transformer to raise the voltage of said circuit to a value corresponding to the higher of said voltages.

2. The method of controlling a circuit supplied with current through a mercury vapor arc device wherein anodes of like polarity are interconnected through an equalizing transformer, which comprises applying different voltages to said anodes, equalizing the currents of said anodes for applying to said circuit a voltage intermediate said voltages, short circuiting a winding of said equalizing transformer to raise the voltage of said circuit to a value corresponding to the higher of said voltages, applying the higher of said voltages to all of said anodes, and removing the short circuit from said winding to equalize the currents of said anodes.

3. The method of controlling a circuit supplied with current through a mercury vapor arc device wherein anodes of like polarity are interconnected through an equalizing transformer, which comprises applying different voltages to said anodes, equalizing the currents of said anodes for applying to said circuit a voltage intermediate said voltages, short circuiting a winding of said equalizing transformer to change the voltage of said circuit to a value corresponding to one of said voltages, applying said voltage to all of said anodes, and removing the short circuit from said winding to equalize the currents of said anodes.

4. The combination of a mercury vapor arc device comprising a cathode and a plurality of anodes mounted within an evacuated chamber, current supply means for simultaneously applying voltages of the same polarity to a group of said anodes, means for interconnecting said device and said supply means to simultaneously apply different voltages to different anodes of said group, and means for equalizing the cur-

rents of the anodes of said group for producing between said cathode and anodes a voltage having a value intermediate said values of said different voltages.

5. The combination of a mercury vapor arc device comprising a cathode and a plurality of anodes, current supply means for simultaneously applying voltages of the same polarity to a group of said anodes, means for equalizing the currents of the anodes of said group, and a single control

means operable successively to cause the anodes of said group to be simultaneously charged to different voltages and to short circuit said equalizing means for changing the voltage between said cathode and anodes to a value corresponding to the higher of said voltages. 15

In witness whereof I have hereunto set my hand this 17th day of December, 1925.

DAVID C. PRINCE.
